UNITED STATES PATENT OFFICE.

FRANK F. SCHWALLER, OF ST. LOUIS, AND THOMAS M. QUINN, OF OVERLAND, MISSOURI.

ARM-REST-HOLDING MEANS.

1,300,883.

Specification of Letters Patent. Patented Apr. 15, 1919.

Application filed May 28, 1917. Serial No. 171,407.

To all whom it may concern:

Be it known that we, FRANK F. SCHWALLER and THOMAS M. QUINN, citizens of the United States, and residing in the city of 5 St. Louis, and Overland, St. Louis county, in the State of Missouri, respectively, have invented a new and useful Arm-Rest-Holding Means, of which the following is a specification.

10 Our invention relates to improvements in arm-rest holding means for convertible chairs, and has for its object to provide an arm-rest holding means so constructed that it may be adjusted to hold the arm-rest 15 at different elevations with relation to the movable back section of a convertible or reclining chair.

A further object of the invention is to provide a device which will be simple in 20 construction, easily adjusted, durable, and neat in appearance.

With the above and other objects in view which will appear hereinafter, our invention consists in the construction, arrangements and combination of parts as will be 25 shown in the drawings, clearly described hereinafter, and finally pointed out in the claims hereto appended.

Referring to the accompanying drawing 30 forming a part of this specification where like characters of reference denote similar parts throughout the several views:

Figure 1, is a side elevation of a convertible chair of the three section type, provided with an arm-rest holding means constructed in accordance with our invention.

Fig. 2, is a detail in perspective, of one of the arm-rest supporting members.

Fig. 3, is a plan view of the ratchet-brace. 40 Fig. 4, is a front elevation of one side of a chair provided with our invention.

Fig. 5, is a detail in sectional elevation, of an arm-rest showing the connection thereto of the arm-rest supporting member and 45 the guide link.

Fig. 6, is a detail in side elevation, in several positions of the forward end of the arm-rest, the arm-rest supporting member and swinging link, as they appear connected 50 to the arm-rest and seat-section.

Referring to the drawings, the reference character 1 designates the seat-section of a convertible chair; 2, the movable back-section; 3, the movable front-section; 4, the 55 supporting legs; 5, a horizontally movable arm; and, 6, an arm fixed to the movable

back-section 2 at one end and pivotally connected to the rear end of the arm 5.

The reference numeral 7, designates an arm rest which is pivotally connected at its 60 rear end, as at 8, to the movable back-section 2. The arm-rest 7 is provided with the outer depending flange 9, and a short inner depending rib 10, as clearly shown in Fig. 5.

A brace member 11 is connected at each 65 end to the front and rear legs 4 of the chair in an inclined position, as clearly shown in Fig. 1. This brace-member 11 is provided with a block 12, approximately midway its ends, and having its upper face 70 provided with the ratchet teeth 13. A slotted opening 14 is formed in the rear end brace member 11, and a slotted opening 15 is formed at the forward end of the brace member 11, as clearly shown in Fig. 3. 75

The reference numeral 16, designates one of the arm-rest supporting members having the inclined upper face 17, the inclined front face or edge 18, and the curved lower end 19 provided with the ratchet teeth 20. 80

The arm-rest supporting member 16 is pivotally connected at its upper front corner by means of a pin 21, to the flange 9 of the arm-rest 7.

The upper rear corner of the arm-rest 85 supporting member 17 is provided with a laterally and inwardly projecting guide-pin 22 which is suitably fixed to the arm-rest supporting member. This guide-pin 22 is adapted to pass through a slotted opening 90 23 in the depending rib 10, and may be provided at its inner end with a suitable thumb-nut 24, as shown in Fig. 5, for locking the parts when desired.

A swinging connecting link 25 is loosely 95 mounted at its upper end upon the guide-pin 22 between the arm-rest supporting member 17 and the depending rib 10, as clearly shown in Fig. 5. The lower end of the link 25 is adapted to be pivotally connected as at 26 to the seat-section 1.

It will be observed, that the flange 9, of the arm-rest 7, forms a guide for the upper end of the arm-rest supporting member 17. The arm-rest supporting member 105 17 and link 24 are both positioned between the flange 9 and rib 10 of the arm-rest 7, as clearly shown in Fig. 5.

It will be observed, from Fig. 6, of the drawings, that the ratchet-teeth 20 of arm-rest supporting member 16 are adapted to engage the teeth 13 of the block 12 when

the back 2 of the chair is in its upright position, or in any of the various inclined positions into which it may be moved, as is manifest.

5 The ratchet-block 12, it will be observed, supports the arm-rest supporting member in its various adjusted positions, as clearly shown in Fig. 6.

It will be here observed, however, that 10 when the back 2 of the chair has been moved to its lowermost or horizontal position, when converting the chair into a couch or bed, the lower end of the arm-rest supporting member 16, is allowed to pass through the opening 14 of the brace member 11 and hang freely from its pivot 21 and guide-pin 22.

To disengage the ratchet-teeth 20 from engagement with the teeth 13 of the supporting block 12, the operator merely leans 20 forward a little in the chair and moves the arm-rests slightly forward upon the swinging connecting link 25. This operation, it will be observed, owing to the arcuate movement of the link 25, raises the teeth 20 of 25 the arm-rest supporting member 16 from engagement with the teeth 13 of the supporting block 12, and then by leaning backward in the chair and pushing rearwardly very slightly against the front edge 18 of 30 the arm-rest supporting member 16, the arm-rest supporting member and the upper end of the link 25 may be moved rearwardly to their desired adjusted positions. When the arm-rest 7 and the back-section 3 have 35 reached the desired adjusted positions, the operator merely raises up slightly upon the front end of the arm-rest and the arm-rest supporting member 16 will then drop into its new adjusted position and the teeth 20 thereof will again engage the ratchet teeth 13 of block 12 and support the arm-rest in 40 its new selected position.

To again raise the arm-rest 7 from any of its lowermost adjusted positions, the operator 45 pulls the movable back 2 forward, thereby moving the arm-rest 7 forward, and through the swinging and raising movement of the link 25, the arm-rest supporting member 16 is moved slightly forward and upward upon the ratchet-block 12 and thereby 50 disengaging the teeth 20 from teeth 13, as is manifest.

It will be observed that the arm-rest 7 may be moved slightly forward when desired by merely forcing the front-section 3 rearward causing it to move the horizontally movable arm rearwardly, which in turn imparts a forward pressure upon the movable back-section 2, and which back in turn moves 55 the arm-rest forward, supported, of course, in this movement by the link 25, as is manifest.

It will be observed that the slotted opening 23 of the rib 10 permits the slight upward swinging movement of the upper rear 60

corner of the arm-rest supporting member 16, when downward pressure is brought to bear upon the arm-rests 7 for releasing the teeth 20 of the arm-rest supporting member 16, from the teeth 13, of the rack 12. This slight arcuate movement of the swinging link 25 and of the arm-rest supporting member 16, is only sufficient to positively release the two sets of teeth from engagement with one another to permit the rearward adjustment of the movable back 2, and simultaneously therewith the lowering of the arm-rest 7, which arm-rest 7, is, of course, again supported by means of the member 16 after it has been readjusted and supported by the rack 12.

From Fig. 6, of the drawings, it will be clearly seen that the slight forward movement of the arm-rest moves the upper end of the link 25 forward and slightly upward, 85 moving the pin 22 from the lower end of the slot 23 to a position near the upper end thereof and at the same time withdrawing the teeth 20 of the arm-rest supporting member 17 from engagement with the teeth 13 of rack 12, as clearly shown in dotted lines marked "A". The dotted lines marked "B" represent the arm-rest 7, and arm-rest supporting member 16 after slight pressure has been exerted upon the front edge thereof and 90 moving pin 22 to top of slot 23. The dotted lines "C" represent the arm-rest 7, link 25, and arm-rest supporting member 16 in a new adjusted position from that shown in full lines. The dotted lines marked "D" represent the arm-rest supporting member 16 in 95 its lowermost position. It assumes this position only when the back-section 2 is lowered to form a bed or couch of the chair.

Only one of the arm-rests and its connections has been described in the specification and illustrated in the drawings, but as the two employed in a chair construction are just alike, it is not thought necessary to describe or illustrate but one side of the chair. 100

The many advantages of the herein described arm-rest supporting and adjusting means will readily suggest themselves to those skilled in the art to which it appertains.

We are aware that various slight and minor changes may be made in the exact construction and location of the several parts, hence reserve the right to make any such changes as may fairly fall within the 115 spirit of our invention and scope of the appended claims.

What we claim is:

1. In combination with the movable back-section of a leg supporting chair having a seat-section, of an arm-rest having a depending outer flange pivotally connected to the movable back-section, a rib depending from said arm-rest having a slotted opening, an arm-rest supporting member pivot- 120

125

130

ally connected at its upper front corner to said arm-rest, a pin fixed to the upper rear corner of said arm-rest supporting member and adapted to pass through the slotted 5 opening in the aforesaid rib, a link pivotally mounted upon said pin at its upper end and pivotally connected at its lower end to the seat-section of said chair, teeth formed in the lower edge of said arm-rest supporting 10 member, and means carried by the chair for supporting said arm-rest supporting member in various selected elevations.

2. In combination with a leg supported chair having a seat-section, a movable back-section and a movable front-section capable of being adjusted to form a bed, of an arm-rest for each side of the chair pivotally connected at their ends to the movable back-section, a rib fixed to each arm-rest having 20 a slotted opening, an arm-rest supporting member pivotally connected at its upper

front corner to the forward end of each arm-rest, a guide pin fixed to the upper rear corner of each arm-rest supporting member adapted to pass through the slotted opening in each of the aforesaid ribs, a guide link mounted at its upper end to each of the aforesaid guide pins and pivotally connected at their lower ends to the seat-section of the chair, ratchet teeth formed at the lower edge 30 of each arm-rest supporting member, and means supported on each side of the chair for supporting said arm-rest supporting member in several adjusted positions for holding said arm-rest at various elevations 35 and the back seat-section of the chair in several inclinations.

In testimony whereof, we have hereunto signed our names to the specification.

FRANK F. SCHWALLER,
THOMAS M. QUINN.
